FIG. 2

UNITED STATES PATENT OFFICE.

FRANKLIN E. ABBOTT, OF BUFFALO, NEW YORK.

COMBINED RAILROAD-RAIL AND RAIL-BASE PLATE.

No. 857,781.

Specification of Letters Patent.

Patented June 25, 1907.

Application filed September 24, 1906. Serial No. 335,955.

REISSUED

To all whom it may concern:

Be it known that I, FRANKLIN E. ABBOTT, a resident of Buffalo, in the county of Erie and State of New York, have invented a new 5 and useful Improvement in a Combined Railroad-Rail and Rail-Base Plate; and I do hereby declare the following to be a full, clear, and exact description thereof.

This invention relates to railway rails, and 10 its object is to provide a rail having the weight very little greater and the same general shape above the flange as standard rails, but one which is balanced as to heads and base and whose strength in the base portion 15 is greater than that of standard forms of rails in use in the United States.

The standard form of railroad rail in use in the United States is of general T form, having a web, a thick, comparatively narrow 20 head, and a thin and comparatively wide base, the latter being flat on its bottom and the flanges having sloping upper faces, said flanges tapering to comparatively thin edges. This form of rail necessitates parting the 25 pass of the reducing rolls at the center of the head and at one edge of the base. Consequently the base portion does not receive any appreciable pressure on the lower face and the edge pressure is not symmetrical.

30 Strains are necessarily set up in the metal. Furthermore, the section is not balanced but there is more metal in the head than in the base; hence, in cooling it bends considerably, making it necessary to camber the same and 35 after it is cool to straighten it. In straightening the same the jaws or "gag" of the straightening press contacts across the entire width of the base, and if the base is not true, heavy strains may be exerted near one or the 40 other edge of the base, thus producing heavy strains at the junction of the base flanges and web. Due to these and other causes, standard forms of railroad rails fracture most frequently at the junction of the web and 45 base flanges, or a line at a, Figure 1.

The object of this invention is to overcome this element of weakness and still have a rail of substantially standard form.

The invention consists of a combined 50 rail and rail base plate, the former being of standard form, except for the base, which is reinforced at the point of usual weakness, and the plate providing a seat or support for such rail.

55 In the accompanying drawing, Fig. 1 is a section through my improved rail and rail

base plate; Fig. 2 is a perspective view of the base plate; Fig. 3 is a bottom plan view thereof; Fig. 4 is a sectional detail on the line 4—4, Fig. 3; and Fig. 5 is a sectional detail showing a modification.

My rail has a head 1, web 2, and base 3, the head and web being of standard form, and the base 3 differing from standard form only

in the fact that it is narrower and reinforced 60 on the bottom. The dotted line 4 indicates the lower face of the usual rail base, and the metal 5 below this line is what I add in order to reinforce the rail at its usual point of weakness.

I make said base narrower than standard forms. The dotted lines 7 indicate the width of the usual rail bases, and the metal 70 saved at the edges of the base of my rail goes into the reinforcement on the bottom, so that

the section is only a few pounds per yard 75 heavier than standard sections. The lower face of the base is straight from the edges to the points 8, and is curved between said points, and the whole is substantially convex.

This section of rail can be produced on 80 rolls whose passes are divided at the centers of both the head and base. As a conse-

quence, the base receives uniform pressure on 85 all parts, while the convexity of the lower face enables the edges of the roll passes to be

sloping, thus exerting an inward pressure di- 90 rectly on the lower face and compacting the metal in a manner impossible with present forms of rails. As a result, the rail base has

no internal strains and is also more compact 95 and hence stronger than old forms of rails. Furthermore, the section is balanced, i. e.

there is as much metal in the base as in the 100 head, and hence in cooling it will not curve nearly so much as standard forms, and the

straightening is reduced to a minimum with 105 a consequent reduction in internal strains. Furthermore, in straightening the same, the

jaw or "gag" of the straightening press bears 110 only on the highest or central portion of the convex base, so that there is not the danger of starting fractures or placing undue strains at the juncture of the base flanges and web.

This form of rail effectually overcomes the 115 weakness in standard forms. This rail may,

if desired, be seated directly in suitable seats 120 cut in the ties, but preferably I employ with

the same a rail base plate 10 having a flat 125 lower face to seat on the tie, and having in its upper face a seat 11 which is the counterpart

130 of the rail base and takes the load directly at the middle of the rail. This plate preferably

is grooved at both sides of the center of its rail seat, as shown at 12, thus giving the thinnest sections at these grooves. As a consequence, in case the plate and rail base should 5 not fit accurately, the plate will yield along these grooves, thereby insuring contact of the rail along the center line of the section and preventing strains at the junctures of the base flanges and web. At the same time the 10 rail is firmly supported not only at its middle as at 14, but also at its edges, as at 15. This base plate is much wider than the rail base, even standard bases, and hence reduces the tendency of the rail to roll.

15 Preferably the plate has a roughened lower face, as shown at 16, Figs. 3 and 4, this preferably being of irregular design, such as may be produced by chisel marks on the surfaces of the reducing rolls. This roughness aids 20 the spikes 17 in keeping the plate from moving on the tie. The plate is provided with a rib 19 on each side of the rail seat, with which ribs the edges of the base flanges contact. Consequently the plate acts also as a gage to 25 preserve the gage of the track. On curves the plate will preferably have its inner rib projected to overhang the rail base, as shown at 20, Fig. 5, which prevents this edge of the base from rising on the outward thrust of the 30 train and consequently prevents the rail from rolling, thus serving the function of the usual brace placed on the outside of the rail on curves. The spike in this case does not contact with the rail base and is not affected by 35 the vertical movement of the rail.

The rail described is of substantially the form of standard rails, so that it can receive

standard fish or joint plates 22, and since the base plate can be seated on any tie, the rail and base plate can be readily substituted for 40 the ordinary rails. Both the rail and base plate are bi-laterally symmetrical, and hence can be applied either end to.

What I claim is:—

1. A combined rail and rail base plate, 45 comprising a rail having a comparatively wide base convex on its lower face, and a base plate provided with a counterpart rail seat.

2. A combined rail and rail base comprising 50 a rail having a comparatively wide base convex on its lower face, and a base plate provided with a counterpart rail seat and with longitudinal grooves in said seat.

3. A combined railroad rail and rail base 55 plate, comprising a rail having a comparatively wide base convex on its bottom, and a base plate having a counterpart seat provided with longitudinal grooves and having ribs at the sides of the seat to contact with 60 the edges of the rail base.

4. A combined railroad rail and rail base plate, comprising a rail having a comparatively wide base convex on its bottom, and a base plate having a counterpart seat and provided on one edge with a rib overhanging the 65 edge of the base.

In testimony whereof, I the said FRANKLIN E. ABBOTT have hereunto set my hand.

FRANKLIN E. ABBOTT.
